(57) **CLAIM**

The ornamental design for a vehicle camera, as shown and described.

DESCRIPTION

FIG. 1 is a top, front and right side perspective view of a vehicle camera showing my new design;

FIG. 2 is a bottom, back and right side perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings depict portions of the vehicle camera in which the design is embodied that form no part of the claimed design.
